UNITED STATES PATENT OFFICE.

WALTER JACOB WOHLENBERG, OF NEW HAVEN, CONNECTICUT.

METER.

1,401,299.

Specification of Letters Patent.

Patented Dec. 27, 1921.

Application filed November 10, 1917, Serial No. 201,412. Renewed November 17, 1921. Serial No. 515,971.

To all whom it may concern:

Be it known that I, WALTER JACOB WOHLENBERG, a citizen of the United States, and a resident of New Haven, in the county of 5 New Haven and State of Connecticut, have invented new Improvements in Meters, of which the following is a full, clear, and exact description.

My invention relates to meters for determining the quantities of fluid or energy flow.

An object of my invention is to have the means of having the fluid's direction of flow deflected by a displaceable surface whereby 15 the displacement of said displaceable surface may be a measure of the rate of flow at given fluid densities.

A second object of my invention is to have the said deflecting surfaces supported at 20 said point of said system of arms, displaceable in a straight line, whereby said deflecting surfaces will be displaced, by variations in the rate of flow, in straight line directions.

25 A third object of my invention is to have the means of having the mechanism respond automatically to variations of density of the fluid being metered, whereby the indications, rates of registering or records will be accurate measures of the weight flow of the fluid.

I accomplish these and other objects of my invention by the structures conventionally disclosed in the accompanying drawings, in which similar characters of reference denote corresponding parts.

Figures 1, 2, 3^a, 3^b, 4^a and 4^b are diagrammatic representations of the conditions of fluid flow existing in the vicinity of the deflecting surface above mentioned and they are included as an aid to the theoretical discussion disclosing the principle of operation.

Fig. 5 represents a longitudinal cross section disclosing certain features of the invention.

Figs. 6^a, 6^b and 6^c are diagrammatic illustrations used in connection with the explanation of the suspension mechanism shown in Fig. 5.

Fig. 6^d shows a special distribution of the suspension points 18 of this mechanism.

Fig. 7 illustrates the mechanism by means of which the magnitudes of the measuring displacements are corrected automatically for variations of the fluid density.

Fig. 8 represents a special form (gravity) of the resisting mechanism against which the measuring displacements are caused to take place.

Fig. 9 represents a special form of the 60 deflecting surface against which the fluid motion acts.

Fig. 10 shows how the deflecting surface may be supported between rollers instead of by the suspension mechanism disclosed in 65 Fig. 5, and Fig. 11 is a cross section showing an assembled view of the principal elements involved in the construction of the meter.

Referring now to Fig. 5, 5 represents the 70 fluid inlet and 7 the outlet from the otherwise leakage proof meter casing 9. The fluid is guided from 5 into 7 by means of the semicircular tube 6 which has in its straight portions holes or vents 8 whereby 75 the static pressure within the space Q will be maintained equal to that within the tube 6.

The tube 6 has fixed to it the rod 10 and the latter is supported by means of pins at 80 21 by links 11. These are supported at their ends by pins 20 by links 12 and 16 and these are in turn supported by means of pins 19 respectively by arms 13, 14 and 15 and 17. These arms are supported by stationary or fixed pins 18. The joints at 18, 19, 20 and 21 are all hinged and such that the parts fastened together thereby are free to rotate with respect to each other about the pin axes as centers. It follows that the 90 whole arm system is free, within given limits, to oscillate about the pins 18.

If now the arms 13, 14, 15 and 17 are of equal lengths and their points of suspension 18 are in parallel lines z—z and z'—z' and 95 if furthermore the links 12 are equal in length to links 16 then points 20 and 21 may be so located that the points 21 will be constrained to move very nearly in the straight line x—x. This is more readily seen by reference to Figs. 6^a and 6^b. Referring first now to Fig. 6^a, there is represented the arrangement of the arms 13 and 14 as shown in the suspension mechanism. Consider that both of these arms may be turned successively about their points of support 18 through equal angles θ , θ_2 , ... In each position let the point p bisect the line joining their extremities. It will in each case fall in the straight line x—x.

100

105

110

Consider now that the arms 13 and 14 are connected by a link as 16 Fig. 6°. If under these conditions, the arm 13 is rotated through an angle θ_1 , then the arm 14 will be 5 rotated through an angle $\theta'_1 > \theta_1$, because, for displacement parallel to $x-x$ of the points 19 of the arms the distance between them increases. Consequently, if the distance is to remain constant, then the point 19 of the 10 lower arm must be displaced a greater amount horizontally. This will operate to cause the mid point p_1 of the link 16 to be displaced a small amount below the line $x-x$ in its new position p'_1 . There will, 15 however, be a point p_2 which is again on this line in the displaced position p'_2 . This point will move a very small amount above the line $x-x$ in the early part of the displacement as will any point p_3 to the left of p_1 . 20 It is obvious now that the arms and link may be chosen of such a length that when properly located a point p_3 will move virtually along the straight line $x-x$. This elementary system of arms as here described is exactly 25 a "Watts straight line motion" and was invented by James Watt.

A still nearer approximation is afforded by the suspension mechanism of Fig 5 which is diagrammatically disclosed in Fig. 6°. 30 In these figures the solid lines show the mechanisms in the central position in which now the arms 14, 12 and 13 and 15, 16 and 17 may be mutually at right angles. It is readily seen that the system of arms 14-12-13 is exactly equivalent to the system 15-16-17 turned 180° about the same axis $x-x$. The linkage system A is connected to the inverted linkage system B at points 20 by means of link 11 having on it a pin of support at 21.

These points p_3 or 20, will be located on the links 16 and 12 of the fundamental elements of the mechanism, as previously explained. Then for a displacement of the systems A and B such that $\theta_1 = \theta'_1$ and $\theta_2 = \theta'_2$, the one point p_3 will be displaced above the line $x-x$ just as much as the other will be displaced below this line. If now the points p_3 are connected by a third link as 11 then 45 the displacement angles θ_1 and θ_2 can not be quite equal respectively to θ'_1 and θ'_2 , and consequently a point 21 located on 11 as p_3 was located on 16 and 12 will move slightly 50 away from the line $x-x$. However, just as 55 the displacement of p_3 from $x-x$ is but a small fractional part of that of the points 19, just so that of 21 will be but a small fractional part of that of p_3 and consequently the variation from the straight line motion 60 may be reduced to a negligibly small amount. If a still closer approximation is desired then it is obvious that the points 21 of two inverted combination systems as described might be connected to a common link and on 65 it would be a point having a motion depart-

ing from the straight line motion but a small fractional part of that of 21.

The tubular arc 6 may thus be suspended by means of the above mechanism and is constrained to have its ends move in virtually straight lines within the pipe ends 5 and 7. There being no mechanical contact between these ends and said pipe ends it follows that the mechanical friction to such a motion can be reduced to a negligible amount 75 by making the arms of said suspension mechanism of such lengths that the motion in the joint is very small.

As shown in Fig. 5 the rod 10 has a collar 23 against which the spring 24 presses. 80 The tension in this spring may be adjusted by means of tension screw 26 having at its end the collar 25 supporting the other end of said spring.

The tube arc 6 has preferably very thin 85 walls so that its inside area is very nearly equal to that of the pipe ends 5 and 7. For such a condition there will be practically constant velocity and uniform flow of the fluid over the path shown. The tubular arc 90 will be perfectly balanced as to static pressure and the only force F_x existing will be due to the velocity of the fluid, or rather due to the deflection from the straight line direction which is caused in its motion by 95 the curved path imposed by the arc. This force will cause the arc to be displaced to the left compressing the spring 24 and the displacements may be transmitted to a shaft 30 rotated by means of lever 29 which has 100 slot 28 into which the pin 27 fits and hence causes the rotation of said lever when the rod 10 is displaced.

These displacements will for a given resistance be governed by the force F_x which 105 is proportional to the product

$$V^2 \delta$$

This can be proven by examining the conditions of flow. Referring to Fig. 1, a 110 represents an elementary mass of fluid flowing around a curved path b c d. The radius of curvature at the instant of consideration is r and V represents the instantaneous peripheral velocity of the element. The 115 radial acceleration of the particle will be then equal to

$$\frac{V^2}{r} \quad (1) \quad 120$$

The volume of the element will be equal to

$$rd\theta \cdot dr$$

if its depth is unity and its mass will then be equal to

$$\frac{rd\theta dr \cdot \delta}{g} \quad (2) \quad 125$$

where δ represents the fluid density and g the acceleration due to gravity. It follows 130

that the radial force dF_c exerted by the particle because of its curvilinear motion will be equal to

$$5 \quad \frac{V^2}{r} r d\theta \cdot \frac{dr \delta}{g} = \frac{dr \cdot \delta}{g} V^2 d\theta \quad (3)$$

The component of this force in a direction $x-x$ will obviously be equal to

$$10 \quad dF_x = \frac{dr \cdot \delta}{g} V^2 \cos \theta d\theta \quad (4)$$

For ideal conditions of flow now both the velocity V and the density δ will remain constant on a circular arc of given radius 15 whence the force dF_x exerted by an arc of fluid of elementary radial depth dr will be equal to (by integration of equation 4 between limits θ_1 and θ_2)

$$20 \quad dF_x = (\sin \theta_2 - \sin \theta_1) \cdot \frac{dr}{g} V^2 \delta \quad (5)$$

$$\sum_{n=1}^{n=n} dF_x = F_x = (\sin \theta_2 - \sin \theta_1) \frac{dr}{g} [V_1^2 \delta_1 + V_2^2 \delta_2 + \dots + V_n^2 \delta_n]$$

Now for ideal conditions of flow the further assumption may be made that $V_1 = V_2 = \dots = V_n$ for obviously with zero friction and zero pressure change this condition will result. Substituting this condi-

50 tion and multiplying by $\frac{n}{n}$ where n represents the number of such arcs of elementary radial depth, there results

$$F_x = (\sin \theta_2 - \sin \theta_1) \frac{V^2 n d r}{g} \left[\frac{\delta_1 + \delta_2 + \dots + \delta_n}{n} \right]$$

in which the product $n d r$ is exactly r_s the 55 radial depth of the sector $i j k l$, and

$$\left[\frac{\delta_1 + \delta_2 + \dots + \delta_n}{n} \right]$$

is exactly δ_m the mean density of this sector. 60 It follows that for this flow as described the force F_x exerted by a sector $i j k l$ will be exactly equal to

$$65 \quad \sin \theta_1 \frac{r_s}{g} V^2 \delta_m \quad (6)$$

We have now to find the relation between the mean density δ_m in the tube arc and that in the straight portion of the pipe.

Referring to Fig. 3^a there is represented 70 a section of a tube in which now the fluid is at rest. We will consider some of the particles m falling on the concentric arcs continued into parallel lines. Obviously now all of the particles in the tube will fall on 75 some one of such lines and a given arc section $i' j' k' l'$ will contain a given number of such particles or molecules. Consider now that each line of particles possesses a uniform linear velocity V as shown 80 in Fig. 3^b. Obviously now in the curved part of the tube these lines of particles will

To find the total force F_x exerted by all of the circular arcs of fluid as 1, 2, ..., n of a given arc of fluid $i j k l$ of Fig. 2 it is merely necessary to sum up the forces of the arcs of elementary radial depth. Consider 25 this fluid arc to be divided into arc sectors each of elementary depth dr and that the density of arc l is δ_1 , of 2, δ_2 etc. to δ_n .

Then obviously any arc sectors as 3 for instance will exert the force 30

$$dF_{x3} = (\sin \theta_2 - \sin \theta_1) \frac{dr}{g} V_3^2 \delta_3$$

and the arc sectors n will exert the force 35

$$dF_{xn} = (\sin \theta_2 - \sin \theta_1) \cdot \frac{dr}{g} V_n^2 \cdot \delta_n$$

Whence the total sectors $i j k l$ will exert the 40 force

become closer together near the outer surface and farther apart near the inner surface and a small element as (a) will have acting on it the centrifugal force dF_c and 85 a force dF_p in the opposite direction due to the inward rate of variation of pressure. For steady flow these forces will be such that

$$dF_c = -dF_p \quad 90$$

and

$$F_p = -\frac{dP}{dr} \text{ or } F_c = \frac{dP}{dr}$$

where $-\frac{dP}{dr}$ is the radial rate of variation of pressure existing in the fluid. 95

Now obviously for ideal conditions of flow each line of these particles will maintain its uniform velocity V about the curve and although the radial space distribution of the successive lines varies there will still be the same number of total lines passing through the sector $i'' j'' k'' l''$ as there are 100 through the sector $i' j' k' l'$ wherein the fluid is at rest. Furthermore, the resultant forces dF_c and dF_p at any point of any line are exactly at right angles to the direction of the line and for ideal flow there is at no 110 point on any line a force between the particles in the direction of the line. Consequently in any given line there is no tendency to alter the distances between the particles on that line although the distances 115 between neighboring particles in the direction of the line may be altered by one line of particles so to speak tending to telescope with a line which in the stationary condition was radially farther separated from it. It 120 follows for any given velocity of flow that in a given time instant exactly the same

number of particles occupy the space $i'' j'' k'' l''$ on the curve, as an equal space $i''' j''' k''' l'''$ cut out of the straight portion will contain, provided that the cross-sectional areas are equal and that the volume cut out in the curved section is a sector as $i'' j'' k'' l''$ containing the whole cross sectional area of flow. In other words the same total mass and weight is contained in each volume 10 so cut out whence

$$\delta_m = \delta$$

or the mean fluid density in the curved 15 section is for the condition of ideal flow exactly equal to the density δ of the fluid in the straight section of the pipe. We may thus substitute for δ_m in (6) the fluid density in the straight section of pipe whence the 20 force F_x is represented as

$$F_x = (\sin \theta_2 - \sin \theta_1) A \cdot \frac{1}{g} V^2 \delta \quad \dots \dots (7)$$

where A has been substituted for the product $l \cdot r_s$ which is obviously the cross sectional area.

Consider now a condition of imperfect flow in which the velocity V may undergo a considerable variation. Referring to Fig. 4^a, 30 $u-w$ represents a straight section of pipe through which the fluid is flowing with a velocity V . If while the fluid is flowing this pipe be bent into the form of an arc as shown by uvw of Fig. 4^b, then possibly both the 35 velocity V and the density δ will be a variable in an arc line. The tendency will obviously be to crowd more particles into the circular arc than existed in the straight pipe length. The mean density would thereby be increased and the mean velocity decreased. 40 These variations would operate to change the magnitude of F_x in opposite senses but since this force varies as V^2 and only directly as δ it follows that the actual force 45 would be, due to such imperfections, somewhat smaller than the force F_x above arrived at. For good conditions of flow this variation will however be very small and negligible.

50 Equation (7) now may be expressed as

$$F_x = KV^2 \delta \quad \dots \dots (8)$$

as all of the terms excepting V and δ will be constant in a given meter. It follows therefore that the displacements caused to the rod 55 10 and hence lever 29 will be proportional to the product $V^2 \delta$. Now the weight of the fluid is proportional to the product $V \delta$.

If now the pressure and temperature of 60 the fluid remains constant then the displacements of rod 10 and lever 29 may directly indicate the weight flow of fluid, for, with δ constant there will be only one value of $V \delta$ for each value of the product $V^2 \delta$. If, however, δ is not constant, that is if the pressure

and temperature of the fluid vary during the flow, then the magnitude of $V^2 \delta$ will not be a conclusive indication of the magnitude $V \delta$ for the flow. In other words for this condition there may be any number of values $V \delta$ 70 for a given product $V^2 \delta$. For instance I; if $V=2$ and $\delta=4$. We have $V^2 \delta=16$ and $V \delta=8$ and II; if $V=4$ and $\delta=1$ then $V^2 \delta=16$ but $V \delta=4$.

Now obviously both conditions I and II 75 will cause the same displacement to the above mechanism but in the one case only half as much fluid is flowing as in the other. It is necessary therefore to take account of the fluid density when this varies during the 80 flow. This is accomplished as follows:

In Fig. 7 the rod 10 is represented as transmitting its displacement through pin 27 to lever 31. In the slot of this lever the bar 34 is adapted to slide and its longitudinal position within the slot is controlled by the diaphragm 42. This diaphragm functions exactly as the diaphragm 31 in Fig. 1 of my application for "fluid meters" Serial Number 198,895. It is a fluid density responsive mechanism and may, as such, be replaced by the other forms of density responsive mechanisms described in said application. As in the former invention, the diaphragm or envelop surrounding the density cell 43 is surrounded by the fluid 90 being metered, and the density fluid contained within the cell may be of the same kind as that being metered, so that at all times the volume 43 will be directly proportional to the specific volume of the surrounding fluid and inversely proportional to the density of the said surrounding fluid. It follows that the displacements of the wall 41 of the envelop will be inversely proportional to the variations of density of the fluid 95 surrounding the cell. The displacements of the wall 41 are transmitted, as shown, to the sliding bar 34 by means of lever 36 and pins 39 and 33. The lever 36 is pinned and free to rotate at 38 and is connected to wall 41 by 100 means of rod 40 and coupling 48.

The zero position of 33 is adjusted by means of coupling 48 and the ratio of magnitudes of longitudinal displacements of 33 to those of 41 may be adjusted by changing the 115 pin 39 to other holes 37 provided for the purpose.

The point 33 now is in the shown arrangement at all times exactly the fulcrum about which the lever 31 is displaced by means of rod 10, so that the arm length l_1 will be inversely proportional to the fluid density surrounding 42.

To the other end of the sliding bar 34, at 35, is pinned the rod 44 which may transmit the displacements of the point 35 through lever 46 and axle 47 to the outside, if so desired.

Suppose now that the rod 10 causes a displacement ΔS of the pin 27, the displacement

of pin 35 caused thereby will obviously be equal to

$$\Delta S_1 \frac{l_2}{l_1}$$

Now l_1 is proportional to $\frac{1}{\delta}$ where δ is the fluid density and if the displacement of rod 10 is caused from a deflecting flow arc as 6 of Fig. 5 then

$$\Delta S_1 \propto V^2 \delta$$

whence

$$\begin{aligned} 15 \quad \Delta S_2 &= V^2 \delta \frac{l_2}{l_1} = l_2 V^2 \delta^2 \\ &= l_2 (V \delta)^2. \end{aligned}$$

But l_2 is practically constant for small displacements ΔS_1 whence for such, the displacements ΔS_2 will be proportional to the quantity

$$[V \delta]^2$$

Obviously for each value of $[V \delta]^2$ there is only one value $V \delta$ whence the displacements ΔS_2 will be an exact measure of the rate of weight flow of the fluid. They will be proportional to the squares of the weight flow of the fluid.

As shown in this system the fulcrum is between the power and resisting connections of the levers. This however is not necessary for the same result will be attained if for instance the fulcrum 33 were interchanged with the resisting connection 35 of the link or if the power and resisting connections were interchanged. The relation in which the displacements ΔS_2 of the resisting connection are proportional to $(V \delta)^2$ will be true as long as the sliding bar or link is provided with the fulcrum and either the resisting or power connections, said remaining connection being provided on the member 31 or guide.

These displacements may, as before shown, be transmitted through a linkage system to axle 47 which may project through the casing.

In a special case it might be desired to have the work of displacement of the force F_x instead of being stored in a spring as 24 be stored in a gravity mechanism as shown in Fig. 8. The rod 10 has a roller 54 pressing against the arm 55 of the pendulum suspended from 56 and having at its other end the weight 57 held in place by the nut 58. If now the rod 10 is displaced an amount s as shown then the pendulum will be displaced to the right. The following equation will be true,

$$Wa = F_x \cdot h$$

$$F_x = W \cdot \frac{a}{h}$$

in which F_x represents the force with which the roller 54 presses horizontally to the left on the pendulum arm in displacing the pendulum. W represents the weight of the pendulum, a the horizontal distance which the center of gravity of the pendulum system is from its point of support 56 and h the vertical distance between the line of action of F_x and the point of support 56. For small angles θ a will be proportional to s whence

$$F_x \propto W \cdot \frac{S}{h}$$

where S represents the horizontal distance of the displacement of the roller 54 from the position it has when in contact with the pendulum arm when the latter hangs vertically. The density mechanism may be applied as before. This arrangement will be particularly advantageous where the resisting mechanism is to be exposed to high temperatures in that its accuracy will not be affected by such high temperatures whereas a spring will lose its temper under such conditions.

Fig. 9 shows a special arrangement of the deflecting surface. In this arrangement t are the surfaces causing the fluid to assume a curved path. The fluid enters through inlet 5' having a definite velocity V . The deflecting tube 6' has a constant total cross sectional area, perpendicular to the direction of flow, at all parts and hence within this tube the velocity V remains constant. The fluid before leaving is divided into two columns and is turned through equal angles θ_s in its flow from the tube 6' and a force $F_x \propto V^2 \delta$ will be exerted along the rod 10 as in the former case, provided the static pressure in the chamber Q' equals that in the tube 6'. This condition may be attained by means of an equalizing pipe as 8'. After leaving 6' the fluid's velocity will be dissipated and the kinetic energy of flow will be returned to the fluid at the pressure existing in Q' . The fluid temperature will thereby be raised and we have from the source region Q , for the velocity V in 5' to the chamber Q' exactly a free expansion of the fluid during 115 which its heat content remains constant. The density fluid of the density correcting mechanism now should for accuracy obviously be exposed to the pressure and temperature conditions of the fluid flowing in 120 the passage 5'. This can be accomplished by providing a chamber as Q'' with an opening as 8'' to 5'. The density chamber and compensating cylinder may then be located within this chamber. For all ordinary rates of 125 flow, however, there will be very small difference in the condition of the fluid in Q' and Q and hence the density mechanism may be located in either. The advantage of this arrangement is that it reduces the necessary 130

length of deflecting arc to a minimum whereby, the errors due to eddy currents on the curved path will be reduced.

In Fig. 10 the transmitting rod 10 is supported on rollers 60 whose axes 61 will be supported in bearings.

An assembled view of an arrangement of the complete metering mechanism is shown conventionally in Fig. 11. The fluid being 10 metered flows through the conduit 70 in which is suspended, by means of rod 73 and links 75 the flow deflecting element 71. This has in it the curved elements 72 tangential to the direction of flow at entrance and then 15 curving as shown so that fluid motion will cause a force F_x to be exerted on 73. The suspending linkage is as shown suspended and connected by pins 77 and 76, so that the links 75 may freely rotate about pins 77 as 20 centers. The element 71 may thus be displaced across the fluid path against small frictional resistance, and if the arms 75 are of sufficient length the relatively small displacements will be virtually in the line $x-x$. 25 The displacements of the element 71 are caused to store energy in a conservative resisting medium such as the spring 111 by means of collar 110 fixed to rod 73. The other end of the spring is supported against 30 the pedestal 112 which is shown bolted to the pressure casing and having opening 113 through which the rod 73 is free to move.

This displacement of the flow deflecting element is as before, transmitted to a lever 35 79 containing a slot 80 in which the bar 81 slides. The position of this bar is controlled by the density responsive diaphragm 42. Instead of a rod 36 with holes 37 as in Fig. 7, this is now shown as a slotted bar 84 in 40 whose slot 85 the block 87 is adapted to slide, so that the position of the fulcrum at 87 may be controlled from the outside by means of bolt head 108 on screw bar 104. This screw bar is fixed longitudinally by means of collars 106 and turns in the threaded base of the diaphragm mechanism at points 103. As the head 108 is turned the diaphragm is moved 45 horizontally and hence the fulcrum 87 is moved longitudinally in the slot 85. At 107 50 packing is provided to prevent leakage. Some of the fluid being metered enters the chamber 109 through the openings 74 so that at all times the diaphragm 42 is surrounded by the pressure and temperature conditions of the 55 fluid being metered.

The pin 82 in the bar 81 is the movable fulcrum controlled by the density mechanism about which the lever 79 is displaced by the flow deflecting element. The pin 83 on 60 the bar 81 may have attached a linkage system 88-89 for the purpose of transmitting the displacements ΔS_2 to a wire or thin rod 93. 91 represents a guiding bearing for the rod which has the wire 93 attached or fixed at the end 92.

This wire 93 now is held in tension by means of a weak spring 96, as the only purpose of this spring is to hold said wire 93 in tension. The wire passes through the meter casing in the hole provided in plug 95 and 70 may be fixed in the head 99 by means of screw 100. The head 99 has a threaded stem over which the adjusting collar 97 screws whence the distance between the spring holding shoulders on 95 and 97 may 75 be adjusted and likewise the initial spring tension may be adjusted.

It follows now that since the wire 93 is continually in tension that it may be very small and still be strong enough to transmit 80 all forces causing displacements ΔS_2 . If the wire 93 is very small then the hole in plug 95 through which the wire passes may likewise be very small. Then even with a small clearance area about the wire such 85 as a small opening will exist that the fluid leakage therethrough will be negligible. This system therefore provides a means of transmitting mechanical displacements involving small forces through a wall between spaces 90 of different fluid pressures and with small leakage of the fluid from the one space to the other. These displacements may be transmitted from head 99 through rod 101 guided in bearing 102 to and indicating registering 95 or recording mechanism.

It is obvious that many changes other than those shown may be made in the arrangement and construction of this apparatus without departing from the spirit and 100 scope of the invention, and therefore I do not wish to limit my invention to the exact arrangements or constructions shown.

Having thus described my invention, I claim as new and desire to secure by Let- 105 ters Patent:

1. In fluid flow meters, the combination, with an element responsive to the flow impulse of the fluid, of an element proportionally responsive to variations of the fluid's 110 density and a lever composed of two members movable lengthwise relatively to each other, said lever being provided with a fulcrum, a resisting connection and a power connection, one of said members, called the link, 115 being provided with the fulcrum and one of said connections, the other member, called the guide, being provided with the other of said connections, said link having its position relatively to said guide mechanically 120 controlled by the element responsive to variations of the fluid's density, said lever having one end mechanically connected with the element responsive to the fluid flow impulse, as and for the purpose set forth.

2. In fluid flow meters, the combination, with an element responsive to the flow impulse of the fluid, of an element responsive to variations of the fluid's density and a lever composed of a guide and a link mov-

elastic fluid within an envelop adapted to be placed in the fluid being metered, said envelop being impervious to the surrounding and confined fluids but being adapted both to 5 conduct heat readily between them and to undergo, because of the forces acting on it due to variations of the surrounding fluid's density, relative displacements of its parts allowing equalization of the internal pressure 10 sure with the external pressure, said envelop having a displaceable part mechanically connected to the link at the fulcrum, said element responsive to the flow impulse comprising a flow deflecting surface mounted in the 15 fluid stream on a carriage displaceable by the flow impulse on said surface, said carriage being connected so as to mechanically transmit its displacements to a mechanically conservative resisting medium and to one 20 end of said lever, as and for the purpose set forth.

8. In fluid flow meters, the combination, with an element responsive to the flow impulse of the fluid, of an element proportionally responsive to variations of the fluid's density and a lever composed of a guide and a link movable lengthwise relatively to said guide, said lever being provided with a fulcrum, a resisting connection and a power 25 connection, said link being provided with the fulcrum and one of said connections, said element responsive to variations of the fluid's density confining a quantity of an elastic fluid of the same kind as the surrounding 30 fluid within an envelop adapted to be placed in the fluid being metered, said envelop being impervious to the surrounding and confined fluids but being adapted both to conduct heat readily between them and to undergo, because of the forces acting on it due to variations of the surrounding fluid's density, relative displacements of its parts allowing equalization of the internal pressure 35 with the external pressure, said envelop having a displaceable part mechanically connected to the link at the fulcrum, said lever having one end mechanically connected to the element responsive to the flow impulse of the fluid, as and for the purpose set forth.

40 9. In fluid flow meters, the combination, with an element responsive to the flow impulse of the fluid, of an element proportionally responsive to variations of the fluid's density and a lever composed of a guide and a link movable lengthwise relatively to said 45 guide, said lever being provided with a fulcrum, a resisting connection and a power connection, said link being provided with the fulcrum and one of said connections, said 50 element responsive to variations of the fluid's density confining a quantity of an elastic fluid of the same kind as the surrounding fluid within an envelop adapted to be placed in the fluid being metered, said envelop being impervious to the surrounding and con-

fined fluids but being adapted both to conduct heat readily between them and to undergo, because of the forces acting on it due to variations of the surrounding fluid's density, relative displacements of its parts 55 allowing equalization of the internal pressure with the external pressure, said envelop having a displaceable part mechanically connected to the link at the fulcrum, said element responsive to the flow impulse comprising a flow deflecting surface mounted in the fluid stream on a carriage displaceable by the flow impulse on said surface, said carriage being connected so as to mechanically transmit its displacements to a mechanically conservative resisting medium and to one 60 end of said lever, as and for the purpose set forth.

10. In the fluid flow path of meters, a flow deflecting surface mounted on a carriage displaceable by the flow impulse on said surface, said carriage being connected so as to mechanically transmit its displacements to a mechanically conservative resisting medium.

11. In the fluid flow path of meters, a curved flow deflecting surface, said curved deflecting surface being at flow entrance tangential to the fluid stream, said curved deflecting surface being mounted on a carriage displaceable by the flow impulse on said deflecting surface, said carriage being connected so as to mechanically transmit its displacements to a mechanically conservative resisting medium.

12. In the fluid flow path of meters, a curved flow deflecting surface, said curved deflecting surface being at flow entrance tangential to the fluid stream, said curved portion terminating in a straight portion, said curved deflecting surface being mounted on a carriage displaceable by the flow impulse on said deflecting surface, said carriage being connected so as to mechanically transmit its displacements to a mechanically conservative resisting medium.

13. In the fluid flow path of meters, a flow deflecting element, said deflecting element having curved surfaces which are at flow entrance tangential to the fluid stream, said curved portions terminating in straight portions, said deflecting element forming a channel of constant cross sectional area normal to the direction of flow, said deflecting element being mounted on a carriage displaceable by the flow impulse on said deflecting surfaces, said carriage being connected so as to mechanically transmit its displacements to a mechanically conservative resisting medium.

14. In meters, the combination with a chamber, to and from which the metered fluid flows, of a flow deflecting surface in the path of the inflowing fluid, said deflecting surface being mounted on a carriage displaceable by the flow impulse on the deflect-

ing surface, said carriage being connected so as to mechanically transmit its displacements to a mechanically conservative resisting medium, the conduit surrounding said 5 fluid stream within said chamber having an opening in the surface tangential to the flow lines, as and for the purpose set forth.

15. In meters, the combination with a chamber, having inlet and outlet passages 10 for the metered fluid, of a flow deflecting channel in the path of the inflowing fluid, said inlet and outlet passages being of the same cross sectional area, said deflecting channel being at all sections of substantially

the same area as the inlet and outlet passages 15 to the chamber, and being curved from tangency with the inlet passage into the outlet passage, said deflecting channel being mounted on a carriage displaceable by the flow impulse and reaction on said channel, said 20 carriage being connected so as to mechanically transmit its displacements to a mechanically conservative resisting medium, the conduit surrounding said fluid stream within said chamber having an opening in 25 the surface tangential to the flow lines, as and for the purpose set forth.

WALTER JACOB WOHLENBERG.
